VALÈRE A. FYNNE, OF ST. LOUIS, MISSOURI, ASSIGNOR TO WAGNER ELECTRIC MANUFACTURING COMPANY, OF ST. LOUIS, MISSOURI, A CORPORATION OF MISSOURI.

IGNITION-SWITCH.

1,397,277.

Specification of Letters Patent. Patented Nov. 15, 1921.

Application filed March 7, 1918. Serial No. 221,066.

To all whom it may concern:

Be it known that I, VALÈRE A. FYNNE, a subject of the King of England, residing at the city of St. Louis, State of Missouri, 5 United States of America, have invented a certain new and useful Ignition-Switch, of which the following is such a full, clear, and exact description as will enable any one skilled in the art to which it appertains 10 to make and use the same, reference being had to the accompanying drawings, forming part of this specification.

My invention relates more particularly to battery ignition systems, such as are used on 15 self-propelled vehicles operated by an internal combustion engine which is started by a cranking motor operated from the battery, or by means of some other mechanical device. Such systems are usually of the normally closed type and if the operator omits 20 to open the ignition switch and the timer happens to stop in its closed position, then the battery is uselessly drained and may be entirely discharged while the car is at rest.

25 In carrying out my invention, as applied to a system including a cranking motor, I provide in the ignition circuit a switch controlled by the speed of the engine and adapted to interrupt the ignition circuit 30 when the engine speed falls below the lowest operating speed, and suitably interconnect same with the starting switch for the cranking motor with a view to making the ignition circuit independent of the speed 35 controlled switch during the starting operation and placing same under the control of said switch when the starting operation is completed. This starting switch is preferably spring controlled and connects the 40 cranking motor to the battery.

45 My invention will be better understood by reference to the accompanying drawing, which is a diagrammatic representation of one embodiment thereof.

Referring to the figure, the storage battery 2 is located within the low tension of 50 primary ignition circuit which comprises the primary 4 of the spark coil 3, the timer 6, 7, the centrifugal ignition switch 12 and the hand operated ignition switch 14. The 55 high tension winding 5 of the spark coil 3 is grounded at one end and connected to the distributor 8 at the other. The spring controlled hand operated switch 15 is adapted to shunt the centrifugal ignition switch 12 and is normally open. The cranking motor

20, 21 is permanently connected to one pole of the battery 2 and is adapted to be connected to the other pole by means of the starting switch 17. This starting switch 60 is also adapted to complete the primary ignition circuit, independently of the centrifugal, or the hand operated ignition switch. This starting switch is spring controlled and normally open. The distributor, the 65 timer, and the centrifugal switch are driven from the engine. The cranking motor is adapted to drive the engine in some well known manner. In the drawing, the centrifugal switch is carried on a shaft 11, provided with a pulley 13 driven from the engine while the contact plate 12 of said switch is insulatingly supported by a sleeve adapted to slide up and down the shaft 11 under the influence of the weights 10. When 75 these weights fly out, the plate 12 is raised and closes the primary ignition circuit. At very low speeds, or with the engine at rest, the weights 10 hold the plate 12 away from the stationary contact with which it co- 80 operates.

The operation of this improved ignition system is as follows: Assuming all the switches to be open, the switch 14 should first be closed and the engine can be started by closing the starting switch 17. The closing of this latter switch connects the negative terminal of the battery 2 to the field winding 20 of the cranking motor through the stationary contact 18 and the lever of 90 the switch 17. The other end of the exciting winding 20 is permanently connected to the positive pole of the battery 2 through the armature 21 of the cranking motor, but the closing of the switch 17 also completes the 95 primary ignition circuit by conductively bridging the contacts 16 and 18. As soon as the engine has begun to fire and operates independently of the cranking motor, the starting switch 17 may be released, for the 100 centrifugal switch is so set that it will close at or near the lowest idling speed of the engine. Should the engine speed now fall below its lowest operating value or should the engine stop altogether, then the centrifugal switch 12 will interrupt the primary ignition circuit and positively prevent all useless drain on the battery, even though the operator omits to open the hand operated ignition switch 14. If it is desired to interrupt the ignition while the engine is running, then it is only necessary to open switch 110

14. In order to reinstate ignition under the same condition, it is only necessary to close switch 14.
- Should it for some reason be desired to 5 start the engine without the use of the cranking motor, as for instance, when the battery is very low, then switch 15 should be closed during the starting period, after switch 14 has been closed. If switch 15 remains closed after the engine has started, then the centrifugal switch is rendered inoperative. For this reason, it is preferred to place the switch 15 under the control of a spring which tends to hold said switch 10 open. If the car is provided with electric lighting or with a charging generator, then the latter, as well as the lamps, can be connected between the conductors 22 and 23 in the usual manner.
- Having fully described my invention, what I claim as new and desire to secure by Letters Patent of the United States is:
1. In an ignition and starting system for internal combustion engines, a starting motor, controlling means therefor, a primary ignition circuit comprising a source of current, a timer and an ignition switch, means governed by the speed of the engine for closing and opening said switch, and means 15 whereby the opening and closing of the motor 20 controlling means opens and closes a circuit in shunt with the contacts of the ignition switch.
2. In an ignition and starting system for internal combustion engines, a starting motor, controlling means therefor, a primary ignition circuit, comprising a source of current, a timer and an ignition switch, means governed by the speed of the engine for closing and opening the switch, and means 25 whereby opening and closing of the motor starting switch opens and closes a circuit in shunt with the ignition switch.
3. In an ignition and starting system for internal combustion engines, a starting motor, a starting switch therefor, a primary ignition circuit, comprising a source of current, a timer and an ignition switch, means governed by the speed of the engine for closing and opening the ignition switch, an auxiliary circuit in shunt with the contacts of the ignition switch, a spring controlled switch in said circuit, the spring tending to hold the switch in open position, and means controlled by the motor starting switch for closing the 30 primary ignition circuit independently of the ignition switch.

In testimony whereof, I have hereunto set my hand and affixed my seal.

VALÈRE A. FYNN. [L. s.]
